(57) **CLAIM**

The ornamental design for an electric scooter, as shown and described.

DESCRIPTION

FIG. 1.1 is a perspective view of an electric scooter showing my new design;

FIG. 1.2 is another perspective view thereof;

FIG. 1.3 is a front elevation view thereof;

FIG. 1.4 is a rear elevation view thereof;

FIG. 1.5 is a left side elevation view thereof;

FIG. 1.6 is a right side elevation view thereof;

FIG. 1.7 is a top plan view thereof; and

FIG. 1.8 is a partially enlarged view of the electric scooter as shown in FIG. 1.1.

The broken lines shown in the figures illustrate environmental subject matter that forms no part of the claimed design.
